UNITED STATES PATENT OFFICE.

MAX STEINER, OF NEWARK, NEW JERSEY, ASSIGNOR TO THE NEW JERSEY SHEET METAL CO., OF NEWARK, NEW JERSEY, A CORPORATION OF NEW JERSEY.

DESIGN FOR A PHONOGRAPH-HORN.

No. 38,602.

Specification for Design.

Patented June 4, 1907.

Application filed May 6, 1907. Serial No. 372,290. Term of patent 7 years.

To all whom it may concern:

Be it known that I, MAX STEINER, a citizen of the United States, residing at Newark, in the county of Essex and State of New Jersey, have invented a new, original, and ornamental Design for Phonograph-Horns, of which the following is a specification, reference being had to the accompanying drawing, forming part thereof.

Figure 1 is a side view, and Fig. 2 is an end view looking from the large end.

What I claim is:—

The ornamental design for a phonograph horn, as shown.

MAX STEINER.
